(57) **CLAIM**

We claim the ornamental design for worksurface bucket, as shown and described.

DESCRIPTION

FIG. 1 is a perspective view of the worksurface bucket embodying the present invention;

FIG. 2 is a front view of the worksurface bucket;

FIG. 3 is a rear view of the worksurface bucket;

FIG. 4 is a first side view of the worksurface bucket with the opposite side view being a mirror image thereof;

FIG. 5 is a top view of the worksurface bucket; and,

FIG. 6 is a bottom view of the worksurface bucket.

The dashed lines and broken lines are for the purpose of illustrating environmental structure and form no part of the claimed design.

1 Claim, 2 Drawing Sheets

FIG. 2

FIG. 3

FIG. 1
